KNIT FABRIC WITH GATHERS THEREIN

Bernard Sapin, New York, N. Y.

Application January 28, 1948, Serial No. 4,786

10 Claims. (Cl. 66—200)

1

The present invention relates to knitted fabrics and to a method of making the same.

The primary object of the present invention is the provision of a knitted fabric having one or more gathered surface portions or sections formed without sewing of the fabric or the use of elastic.

In accordance with my invention, I take a half cardigan knit fabric, which is a well known type of knit fabric, and drop the half cardigan stitches in selected laterally spaced wales or areas of the fabric, or in any other desired area or areas of the fabric, according to the desired design. As a result of dropping the half cardigan stitches in an area of the fabric located between undropped half cardigan stitches, gathers are produced in the area of the dropped half cardigan stitches as a result of the release of the excess yarn introduced in the fabric during the knitting thereof for producing the half cardigan stitches. In other words a half cardigan knit fabric has half cardigan stitches at one side or face of the fabric and cuff stitches on the other side or face thereof produced, as is well known to those familiar with the knitting art, by knitting the fabric on a flat knitting machine with front and back needles in the conventional manner of producing a knit fabric conventionally known as half cardigan. When the half cardigan stitches are dropped, the cuff stitching remains and the yarn released by dropping the half cardigan stitches results in the formation of gathers in the fabric between the areas in which the half cardigan stitches are not dropped. Thus, by the simple operation of dropping the half cardigan stitches from one or more selected portions of the conventional half cardigan knit fabric between portions in which the half cardigan stitches are retained, I am able to produce gathers in the fabric without sewing the fabric or without using elastic material or without performing any other operations or using auxiliary materials.

The invention and the above mentioned and other objects, features and advantages thereof will be fully understood from the following description considered in connection with the accompanying illustrative drawings:

In the drawings:

Fig. 1 is a plan view of a piece of half cardigan knit fabric;

Fig. 2 is a plan view of the fabric produced in accordance with the present invention from the conventional fabric illustrated in Fig. 1;

Fig. 3 is a sectional view on the line 3—3 of Fig. 2, showing the gathers more or less schematically; and

2

Fig. 4 is a view, on an enlarged scale, showing the half-cardigan stitch structure and adjacent rows of wales in which the stitches are dropped.

In Fig. 1 there is shown a piece 10 of half cardigan knit fabric having the selvage edges 12 extending along the length of the fabric, that is, in the direction in which the fabric comes off the knitting machine during the knitting of the fabric. The face 14 of the fabric may be considered as the face of the fabric which has the half cardigan stitches, the opposite side or face of the fabric having the cuff stitches exposed thereon. The fabric is preferably knit from woolen or worsted yarn.

15 In Fig. 2 there is shown a fabric 10A which is provided, in the design selected for illustration, with a plurality of laterally spaced rows of gathers 16 which resemble a plurality of pleats 18 extending laterally between the laterally spaced portions 20 of unaltered half cardigan knit fabric. These gathers or pleats 18 are produced by the simple operation of dropping the half cardigan stitches in the areas of the fabric between the spaced undisturbed portions 20 of the fabric. The half cardigan stitches may be dropped in the selected areas or spaced areas of the fabric for producing the gathers 18 in any suitable way as will be readily apparent to those familiar with the knitting art. It will of course be understood that as a result of dropping the half cardigan knit stitches in a space between groups of wales of half cardigan stitches which are not dropped or disturbed, the yarn which is released as a result of the dropping of said half cardigan stitches in the selected area remains interlaced with or connected to the cuff stitches and to the undisturbed half cardigan stitches. However, due to the release of the half cardigan stitches the portions of the yarn which had previously been looped to form the half cardigan stitches constitute excess yarn in the area or areas of the fabric in which the half cardigan stitches are dropped and thus form gathers or puckers. It will be understood that the number of adjacent wales of half cardigan stitches which are dropped between adjacent laterally spaced groups of wales 20 of half cardigan stitches which are not dropped may vary considerably depending upon the desired effect.

20 As an example, but without limitation, in a fabric which I have produced in accordance with the present invention, a gathered effect of desirable appearance is produced by dropping about 4 or 5 or 6 adjacent longitudinal wales 20 of half cardigan stitches between the adjacent laterally

spaced areas of half cardigan stitches which are not dropped.

The gathered knit fabric of the present invention may be produced in the form of bands for use in trimming garments or other articles of wearing apparel. For example, or without limitation, I have employed a band of such fabric as the top of a sweater, at the shoulders and neck line, but it will be understood that the fabric may be made in wide fabrics as well as in fabrics of band width and that such fabrics may be utilized generally in the manufacture of knit goods as well as for trimmings. It will be understood that the design shown in Fig. 2 is merely illustrative of the invention and is therefore not to be considered as in any way limiting the various gathered areas which may be provided in a half cardigan knit fabric in accordance with my invention as hereinbefore described.

Having thus described my invention, what I claim and desire to secure by Letters Patent is:

1. Knit material comprising a half cardigan knit fabric having a section in which all the half cardigan knit stitches of a plurality of wales are dropped, said section being disposed between laterally spaced groups of wales of the original half cardigan knit stitches of said fabric, the yarn released by said dropped stitches forming gathers in said section.

2. Knit material comprising a half cardigan knit fabric formed of non-inelastic textile yarn and having a section in which all the half cardigan knit stitches of a plurality of wales are dropped, said section being disposed between laterally spaced groups of wales of the original half cardigan knit stitches of said fabric, the yarn released by said dropped stitches forming gathers in said section.

3. Knit material comprising a half cardigan knit fabric having a section in which all the half cardigan knit stitches of a plurality of wales are dropped, said section being disposed between laterally spaced groups of wales of the original half cardigan knit stitches of said fabric, the yarn released by said dropped stitches forming gathers in said section, said section of dropped stitches extending longitudinally of the fabric.

4. Knit material comprising a half cardigan knit fabric formed of non-inelastic textile yarn and having a plurality of laterally spaced sections in each of which the half cardigan knit stitches are dropped, each of said sections being disposed between laterally spaced groups of wales of the original half cardigan knit stitches of said fabric, the yarn released by said dropped stitches forming gathers in said section.

5. Knit material comprising a half cardigan knit fabric having a section consisting of a plurality of adjacent wales of dropped half cardigan knit stitches, and groups of adjacent wales of the original half cardigan knit stitches disposed in laterally spaced relation at the lateral boundaries of said section of dropped stitches, the yarn released by said dropped stitches forming gathers in said section.

6. Knit material comprising a half cardigan knit fabric formed of non-inelastic textile yarn and having a plurality of laterally spaced sections each consisting of a plurality of adjacent wales of dropped half cardigan knit stitches, and groups of adjacent wales of the original half cardigan knit stitches disposed in laterally spaced relation at the lateral boundaries of said sections, respectively, the yarn released by said dropped stitches forming gathers in said section.

7. Knit material comprising a half cardigan knit fabric formed of non-inelastic textile yarn and having a plurality of laterally spaced sections each consisting of a plurality of adjacent wales of dropped half cardigan knit stitches, and groups of adjacent wales of the original half cardigan knit stitches disposed in laterally spaced relation at the lateral boundaries of said sections, respectively, the yarn released by said dropped stitches forming gathers in said section, said fabric having the original half cardigan knit stitches at the opposite side edge selvages of the fabric.

8. Knit material comprising a half cardigan knit fabric having a section in which all the half cardigan knit stitches of a plurality of wales are dropped, said section being disposed between laterally spaced groups of wales of the original half cardigan knit stitches of said fabric, the yarn released by said dropped stitches forming gathers in said section, said fabric having the original half cardigan knit stitches at the opposite side edge selvages of the fabric.

9. Knit material comprising a half cardigan knit fabric having a section in which all the half cardigan knit stitches of a plurality of wales are dropped, said section being disposed between laterally spaced groups of wales of the original half cardigan knit stitches of said fabric, said fabric being knit from woolen yarn and the yarn which is released by said dropped stitches forming gathers in said section.

10. Knit material comprising a half cardigan knit fabric having a section in which all the half cardigan knit stitches of a plurality of wales are dropped, said section being disposed between laterally spaced groups of wales of the original half cardigan knit stitches of said fabric, the yarn released by said dropped stitches forming gathers in said section, said gathers consisting of the cuff stitches and of the interlaced yarn which is released by said dropped stitches.
